ELECTRICALLY HEATED COMB

Samuel L. McNair, Overland Park, Kans., assignor to The Songrand Corporation, a corporation of Missouri

Filed Dec. 12, 1966, Ser. No. 5,006

Term of patent 14 years

(Cl. D86—8)

FIG. 1 is a top plan view of an electrically heated comb embodying my new design;

FIG. 2 is a side elevational view, the side opposite being a mirror image thereof;

FIG. 3 is a bottom plan view;

FIG. 4 is an end elevational view as seen from the left of FIG. 2; and

FIG. 5 is an end elevational view as seen from the right of FIG. 2.

I claim:

The ornamental design for an electrically heated comb, as shown and described.
